UNITED STATES PATENT OFFICE.

GEORGE N. PHELPS, OF BROOKLYN, NEW YORK, ASSIGNOR TO HIMSELF
AND CONRAD BRAKER, JR., OF NEW YORK CITY.

IMPROVEMENT IN APPARATUS FOR REMOVING OILS FROM ANIMAL AND VEGETABLE SUBSTANCES.

Specification forming part of Letters Patent No. 151,050, dated May 19, 1874; application filed April 18, 1874.

To all whom it may concern:

Be it known that I, GEORGE N. PHELPS, of Brooklyn, in the county of Kings and State of New York, have invented a new and useful Improvement in Apparatus for Extracting Oils, of which the following is a specification:

Figure 1 is a vertical section of my improved apparatus. Fig. 2 is an edge view of the same. Fig. 3 is a horizontal section of the same, taken through the line *x x*, Fig. 1. Fig. 4 is a horizontal section of the same, taken through the line *y y*, Fig. 1. Fig. 5 is a detail view of one of the buckets.

Similar letters of reference indicate corresponding parts.

My invention has for its object to furnish an improved apparatus for removing oils, fats, resins, &c., from solid material, by treating it with bisulphide of carbon or other suitable solvent, and which shall be simple in construction, convenient in use, and effective in operation.

The invention consists in the arrangement of the endless chains of buckets, the shelves, the semi-cylindrical plates, and the vertical plate, in connection with each other and the case of the machine, to form a zigzag passage through which the solid material may be carried against a stream of a solvent; in the strainer-buckets, in combination with the endless chains, and the shelves and plates; in the strainers formed in the upper shelves for draining off the solvent after the solid matter has been carried through said solvent; and in the combination of one or more coils of heating-pipe with the upper shelves and the endless chain of buckets, as hereinafter fully described.

A represents a high, wide, and thin or shallow case, the size of which must depend upon the amount of work required to be done by the apparatus. *B* is a series of horizontal shelves, the alternate ends of which are connected by semi-cylindrical plates *b¹*, as shown in Fig. 1, so as to form a continuous passage from the bottom to the top of the case *A*. At one side edge of the case *A* the semicircular plates *b¹* are placed close to the edge wall. At the other side edge of the case *A* the semicircular plates *b¹* are placed at a little distance from the edge wall, and a vertical plate, *C*, is

secured to them, so as to form a vertical passage of the same size as, and being a continuation of, the other or zigzag passage. To the case *A*, at the free ends of the shelves *B* and plate *C*, are pivoted pairs of pulleys *D*, around which pass endless chains *E*. To the chains *E* at suitable distances apart are attached buckets *F*, which are formed of perforated sheet metal, or by attaching wire-gauze to a metallic frame, so as to allow the liquid to pass through while carrying the solid material along the endless passage. The oil is extracted from the solid material by bisulphide of carbon or other suitable solvent, which is introduced through the inlet-pipe *a¹*, and withdrawn when saturated, or nearly so, through the outlet *a²*, which is placed in the lowest compartment of the zigzag passage, near the lower end of the vertical part of said passage. The inflow of the solvent should be so regulated as to fill the lower part of the case nearly to the inlet *a¹*. The solid material is introduced through a feed-spout, *G*, in the case *A*, a little higher than the inlet *a¹*, is carried by the buckets *F* down through the solvent, and up from one shelf to another through the zigzag passage, and is discharged through the discharge-spout *H*. The upper shelf *B* is inclined, to obtain space for the mouth of the discharge-spout *H*, beneath the upper end of the said shelf, so that, as the buckets *F* push the solid material from the upper end of said inclined shelf, it may drop into the said spout and pass out of the machine. Some or all of the shelves *B* above the water-line of the machine have openings formed in them, closed with finely-perforated plates or wire-gauze *b²*, to allow the solvent draining from the solid material to flow through, and thus pass back to the lower part of the machine. One or more of the shafts of the chain-pulleys *D*, according to the length of the chains, pass through the casing *A*, and have screw-wheels *I* attached to them, the screw-teeth of which mesh into the thread of an endless screw, *J*, which may be driven by a band and pulleys, or other suitable gearing from any convenient power. In the case *A* above the water-line of the solvent are formed openings, one or more, in which are inserted pipes *K*, through which the vapors escape,

which vapors are designed to be conducted to a condenser and condensed for future use. L are coils of steam or hot-air pipes, placed in the upper part of the case A, between the shelves B, to dry the solid material; or rather to expel the solvent from said material, so that the least possible amount of the said solvent may be carried out with the refuse and wasted.

By this construction, the inflowing stream of the solvent meets the solid material as it rises above the water-line of the solvent, and thus removes any oil that may remain in it after passing through the solvent. The solvent and the solid material pass through the lower part of the machine in opposite directions, and the solvent flows out as it meets the solid material, as said solid material reaches the lower end of the vertical part of the passage, so that the solvent may be as near saturation as possible when it flows from the machine. The solvent and oil, as they escape from the machine, are conducted to a still, where they are separated, and the solvent may be again used.

I am aware of the existence of a patent granted to E. S. Hutchinson, April 30, 1872, No. 126,300, and I disclaim as my invention anything shown and claimed in said patent.

Having thus described my invention, what I claim as new, and desire to secure by Letters Patent, is—

1. The arrangement of the endless chain of buckets E F, the pulleys D, the shelves B, the semi-cylindrical plates b^1 , and the vertical plate C, in connection with each other and the case A, substantially as herein shown and described, to form a zigzag passage, through which the solid material may be carried, against a stream of a solvent, as set forth.

2. The strainer-buckets F, in combination with the endless chains E, and the shelves B and plates b^1 , substantially as herein shown and described.

3. The strainers b^2 , formed in the upper shelves B, for draining off the solvent after the solid matter has been carried through said solvent, substantially as herein shown and described.

4. The combination of one or more coils of heating-pipes, L, with the upper shelves B and endless chain of buckets E F, substantially as herein shown and described.

GEORGE N. PHELPS.
